Primary Examiner — T Chase Nelson*Assistant Examiner* — Kelly L Gross(74) *Attorney, Agent, or Firm* — Renner, Otto, Boisselle & Sklar, LLP(57) **CLAIM**

The ornamental design for a medical device, as shown and described.

DESCRIPTION

FIG. 1 is a front perspective view of the medical device showing an embodiment of our new design;
FIG. 2 is a rear side elevation view thereof;
FIG. 3 is a front side elevation view thereof;
FIG. 4 is a right side elevation view thereof;
FIG. 5 is a left side elevation view thereof;
FIG. 6 is a top plan view thereof; and,
FIG. 7 is a bottom plan view thereof.

The broken lines illustrate unclaimed portions of the article or its environment and form no part of the claimed design.

1 Claim, 7 Drawing Sheets(56)
